UNITED STATES PATENT OFFICE.

EDWARD ERMOLD, OF NEW YORK, N. Y.

LABELING MACHINE.

Original application filed January 6, 1926, Serial No. 79,526. Divided and this application filed July 30, 1926. Serial No. 125,849.

This invention relates to labeling machines, and more particularly to a mechanism for dating labels to be automatically applied to bottles or other containers as evidence of the 5 date when said label was applied to the bottle at the plant of the manufacturer of the product vended therein; the subject matter of the present application constituting a division of my pending application for Patent No. 10 79,526, filed January 6, 1926.

It is a more particular object of my invention to provide a very simple, automatically actuated mechanism for labeling machines whereby the date is successively stamped upon 15 the labels contained in the magazine prior to their withdrawal from said magazine by the label picker mechanism.

More particularly, I propose to provide such a mechanism for use in conjunction with 20 machines which simultaneously apply labels to a plurality of bottles or containers, the said mechanism in one embodiment thereof consisting essentially of a horizontally disposed bar pivotally mounted in the machine frame 25 at its opposite ends and carrying a plurality of arms provided with the dating stamps and associated with the respective magazines together with an actuating means for oscillating said bar to move the dating stamps away 30 from the magazines and out of the path of a reciprocating label picker, and means for pivotally moving the bar in an opposite direction independently of said actuating means to cause the forcible impact of the dating 35 stamps upon the labels.

It is also a further general object of my invention to provide a date stamping mechanism for labeling machines which is simple in construction, positive and reliable in its 40 operation and may be readily adapted to various types of labeling machines without greatly increasing the manufacturing cost thereof.

With the above and other objects in view, 45 the invention consists in the improved date stamping mechanism, and in the form, construction and relative arrangement of its several parts as will be hereinafter more fully described, illustrated in the accompanying 50 drawings, and subsequently incorporated in the subjoined claims.

In the drawing, wherein I have illustrated one simple and practical embodiment of the invention and in which similar reference

characters designate corresponding parts throughout the several views,—

Fig. 1 is a fragmentary sectional view through one end of a bottle labeling machine equipped with my improved date stamping mechanism and showing one position of the 60 dating stamps, and

Figs. 2 and 3 are detail vertical sectional views showing other positions which the stamp carrying arms assume with respect to the movable label picker at different points 65 in the operation thereof.

In the accompanying drawings, I have illustrated only so much of the labeling machine as is essential to a clear understanding of my present improvements, the said machine in general being of the same construction as that disclosed in Patent No. 1,308,280, issued to me on July 1, 1919. For the purposes of this explanation, I have herein shown one 70 of the conveyer shafts 10 on which the sprockets 11 for the conveyer chains 5 are suitably fixed. Between these chains and suitably attached thereto the bottle receiving and conveying flights 7 are arranged. This conveyer 75 is operatively mounted within a suitable 80 frame structure indicated at 8.

From an inspection of my issued patent, it will be observed that it is provided with vertically movable label pickers automatically actuated in the operation of the machine so 85 that at the proper time a single label is withdrawn from the magazine and then positioned in the path of movement of a bottle. In the accompanying drawing, I have shown 90 one of these label pickers at 36 and the label receiving magazine at 37. The upper end of the label picker is provided with an angular bracket 38 upon which there is suitably mounted an ink absorbing roller 39.

A bar 41 extends horizontally across the 95 front of the machine and is pivotally supported at each of its ends as at 40 upon the machine frame 8. This bar carries a series of depending arms 42 corresponding in number with the number of the label magazines 37 100 and in the lower end of each of said arms, one or more dating stamps 45 are removably mounted.

Any convenient means may be provided for the operation of the dating stamps at the 105 proper time, and for this purpose, I have herein disclosed an arm 49 fixed to one end of the bar 41 and with which the upper end

of a rod 50 is pivotally connected, said rod at its lower end having a yoke 51 straddling the shaft 10 and provided with a roller 52 engaged by the cam 53 fixed on said shaft. The 5 vertically movable label picker 36 may be actuated by means similar to that shown in my issued patent.

In the operation of the mechanism above described, it will be understood from reference to Fig. 3 that in the downward movement of the label picker, the ink roller 39 presses against the type faces of the dating stamp 45 and coats the same with ink. The dating stamp is moved to this position through the medium of the cam 53 operating the rod 50 against the action of a coil spring 55 and after the label picker has passed below the dating stamp as shown in Fig. 1, the said spring 55 contracts, thereby rocking the bar 41 in the opposite direction and forcibly engaging the several dating stamps under considerable pressure against the faces of the end labels in the respective magazines 37, thereby imprinting the date thereon. In the upward movement of the label picker 36, cam 53 operates rod 50 to rock the bar 41 and move the dating stamps to substantially the position shown in Fig. 2 of the drawings and out of the path of movement of the label picker so that the latter may move above the dating stamps to a position for movement against the dated labels. Thereafter, the label picker is moved away from the magazines, thus withdrawing the dated labels and is then lowered to position such labels in the path of movement of the bottles carried by the conveyor 5.

In the manner above described, the stamps 45 apply to the gummed surface of the outermost label in each magazine 37, the date upon which the bottles are labeled. Thus, this date cannot be changed after the label has been applied to the bottle and should any question thereafter arise as to the age of the product contained in the bottle the date upon which the bottle was labeled and placed upon the market can be incontestably established by simply removing the label and noting the date upon the gummed side thereof.

From the foregoing description considered in connection with the accompanying drawings, it is believed that the construction, manner of operation and several advantages of my present improvements will be clearly and fully understood. Such an automatic dating mechanism as above explained is a very desirable addition to machines for labeling bottles or other containers, as many manufacturers desire to inform the public as to the date of bottling and labeling the product so that the public may be thus assured as to the freshness thereof. As such date is applied to the gummed side of the label, it cannot be fraudulently altered or changed by the retailer.

This dating mechanism is however, very sim-

ple in its construction, consisting of relatively few parts which are positive and reliable in their operation and not liable to get out of order. Therefore, the addition of this dating mechanism to labeling machines as now in general use may be made at nominal cost. While I have herein shown and described an example of my present improvements which I have found to be entirely satisfactory in practical operation, it is nevertheless to be understood that the essential features thereof might be exemplified in numerous other alternative structures, and I therefore, reserve the privilege of making all such legitimate changes therein as may be fairly embodied within the spirit and scope of the invention as claimed.

I claim:

1. In a labeling machine having a label magazine and a label picker operable to singly withdraw the labels from said magazine, an arm pivotally supported at one of its ends above the magazine, a dating stamp carried by the other end of said arm and movable therewith across the path of movement of the label picker, means for positively moving said stamp carrying arm out of the path of movement of the label picker as the latter is moved to its label receiving position, and additional means for moving said arm in the opposite direction after the label picker is withdrawn from label receiving position to engage said dating stamp with the outermost label contained in the magazine.

2. In a labeling machine having a label magazine and a label picker operable to singly withdraw the labels from said magazine, an arm pivotally supported at one of its ends above the magazine, a dating stamp carried by the other end of said arm and movable therewith across the path of movement of the label picker, means for positively moving said stamp carrying arm out of the path of movement of the label picker as the latter is moved to its label receiving position, additional means for moving said arm in the opposite direction after the label picker is withdrawn from label receiving position to engage said dating stamp with the outermost label contained in the magazine, and means carried by said label picker to ink the type faces of the dating stamp in the movement of the label picker to its label receiving position.

3. In a labeling machine having a label magazine and a movable label picker to singly withdraw the labels from said magazine, a rock shaft, a dating stamp carried by said rock shaft for movement towards and from the label magazine, cam operated means for actuating said rock shaft to move the dating stamp when the label picker is withdrawn from its label receiving position and imprint the date upon the outermost label contained in the magazine, and an inking roller carried by said label picker contacting with the type

faces of the dating stamp in the movement of the label picker to its label receiving position.

4. In a labeling machine having a label magazine and a label picker operable to singly withdraw the labels from said magazine, label dating mechanism including a dating stamp movable towards and from the label magazine, means for positively actuating said stamp to move the same away from the magazine and permit the label picker to move into opposed relation thereto, means operable dur-

ing such movement of the label picker to ink the type faces of the dating stamp, and means for moving said dating stamp in the opposite direction independently of said actuating means after the label picker has been withdrawn to cause the forcible impact of the dating stamp against the outermost label of the magazine. ¹⁵

In testimony that I claim the foregoing as my invention, I have signed my name hereto. ²⁰

EDWARD ERMOLD.
